UNITED STATES PATENT OFFICE.

WILLIAM BRYSON, OF FIFIELD, WISCONSIN.

RAILWAY-TIE.

SPECIFICATION forming part of Letters Patent No. 762,132, dated June 7, 1904.

Application filed November 10, 1903. Serial No. 180,551. (No model.)

To all whom it may concern:

Be it known that I, WILLIAM BRYSON, a citizen of the United States, and a resident of Fifield, in the county of Price and State of Wisconsin, have invented a new and Improved 5 Railway-Tie, of which the following is a full, clear, and exact description.

This invention relates to improvements in cross-ties for railways, an object being to provide a steel or other metal tie that will be strong and durable, yet comparatively light; and another object is to provide a novel form 10 of spikes for securing the rails to the tie.

I will describe a railway-tie embodying my 15 invention and then point out the novel features in the appended claims.

Reference is to be had to the accompanying drawings, forming a part of this specification, in which similar characters of reference indicate corresponding parts in all the figures.

Figure 1 is a perspective view of a railway-tie embodying my invention. Fig. 2 is a sectional elevation of the same. Fig. 3 is a section on the line *xx* of Fig. 2, and Figs. 4 and 25 5 are perspective views of the rail-fastening spikes.

The tie comprises a plurality of longitudinally-disposed metal plates 1, the said plates being vertical in the direction of their width. 30 The several plates are spaced apart, and between the plates at the ends are plates or blocks 2, through which fastening-bolts 3 pass, the said bolts also passing through the main tie-plates. Also arranged between the plates 35 underneath the rails are locking plates or blocks 4, which are serrated or notched at their opposite sides, as indicated at 5. Also secured between the tie-plates and spaced from the locking plates or blocks are abutment plates or blocks 6. These several plates 40 or blocks are secured to the plates of the tie by bolts. The space between the plates or blocks 6 and the plates or blocks 4 is sufficient to permit the insertion of the locking-spikes 45 7 and the key-spikes 8. The locking-spikes 7 are provided with teeth 9 for engaging in the notches of the locking plates or blocks. The spikes 7 have heads 10 for engaging on

the bottom flanges of the fish-plates 11, and the key-spikes 8 have heads 12 for engaging on 50 the top plate 13 of the tie. The space between the several plates 1 opens outward at the bottom, and this space may be packed with dirt.

In the operation the rails are placed on the 55 tie, then the locking-spikes 7 are inserted, after which the key-spikes 8 are driven in, forcing the locking-spikes 7 into locking engagement with the plates or blocks 4, as clearly indicated in Fig. 2.

Having thus described my invention, I claim as new and desire to secure by Letters Patent—

1. In a railway cross-tie, blocks in the tie underneath the rails and having notches at the opposite sides, spikes having teeth for engaging 65 in the notches, and key-spikes.

2. A railway cross-tie comprising a plurality of parallel metal plates, plates or blocks arranged between said parallel plates underneath the rails, the said plates or blocks being notched at the opposite sides, stop plates or blocks outward from the locking plates or blocks, spikes having teeth for engaging in the notches of the locking-blocks, and key-spikes for engaging between the said toothed 75 spikes and the last-named plates or blocks.

3. A railway cross-tie comprising a plurality of longitudinally-extended metal plates, the said plates being vertical in the direction of their width, spacing-blocks between the 80 plates, bolts passing through the blocks and plates, and means for securing the rails to the tie.

4. The combination with a railway cross-tie, of means for securing a railway-rail thereto, the said means comprising a notched block in the tie, and a spike having teeth for engaging in said notches.

In testimony whereof I have signed my name to this specification in the presence of two sub- 90 scribbling witnesses.

WILLIAM BRYSON.
